This application claims priority to and the benefit of
Switzerland Plant Breeders Rights application filed on Jun.
3, 2015, Application No. 15-3012, the entire contents of
which are incorporated herein by reference for all purposes.

An application with the European Community Plant Vari-
ety Office was filed on Jul. 2, 2015, File No. 2015-1525.

BACKGROUND OF THE NEW PLANT

The present invention comprises a new and distinct variety of *pelargonium*, botanically known as *Pelargonium zonale* and hereinafter referred to by the variety name 'KLEPZ15357'. 'KLEPZ15357' originated from a cross-combination in June 2009 in Stuttgart, Germany between the female *pelargonium* variety 'PZ-2002-0037' (unpatented) and the proprietary male *pelargonium* variety 'PZ-2005-0031' (unpatented).

Seeds from the cross-combination in June 2009 in Stuttgart, Germany were obtained. The seeds were sown and plants were grown for evaluation. A single plant was selected in May 2010 and subsequently named 'KLEPZ15357'. In August 2010 'KLEPZ15357' was first vegetatively propagated by vegetative cuttings from stems.

2

'KLEPZ15357' was found to reproduce true to type in
successive generations of asexual propagation via vegetative
cuttings in Stuttgart, Germany.

SUMMARY

The following are the most outstanding and distinguishing
characteristics of this new variety when grown under
normal horticultural practices in Stuttgart, Germany.

1. Red flowers; and
2. An upright and compact growth habit.

DESCRIPTION OF THE PHOTOGRAPH

15 This new *pelargonium* plant is illustrated by the accom-
panying photograph which shows an overall view of the
plant. The photograph is of an approximately ten-week-old
plant grown in Stuttgart, Germany under greenhouse con-
ditions in May 2014. The colors shown are as true as can be
20 reasonably obtained by conventional photographic pro-
cedures.

DESCRIPTION OF THE NEW VARIETY

25 The following detailed descriptions set forth the distinctive
characteristics of 'KLEPZ15357'. The data which
define these characteristics were collected from asexual
reproductions carried out in Stuttgart, Germany. Data was
collected on plants grown 2-months after planting in Stuttgart.
